**SERVICE STATION DISPLAY CABINET OR
SIMILAR ARTICLE**

Joseph A. Winger, Myron R. Cothorn, and Murry J. Gammill, Greenwich, Conn., assignors to Texaco Inc., New York, N.Y., a corporation of Delaware

Filed Mar. 18, 1964, Ser. No. 79,061

Term of patent 14 years

(Cl. D80—11)

FIGURE 1 is a front elevational view of a service station display cabinet or similar article showing our new design;

FIGURE 2 is a right side elevation;

FIGURE 3 is a rear elevation view;

FIGURE 4 is a fragmentary transverse cross-section taken along the lines 4—4 of FIGURE 1 looking in the direction of the arrows;

FIGURE 5 is a left side elevation view; and

FIGURE 6 is a top plan view.

The dominant features of our design reside in the portions shown in full lines.

We claim:

The ornamental design for a service station display cabinet or similar article, as shown and described.
